UNITED STATES PATENT OFFICE.

SETH H. LEAVENWORTH, OF CINCINNATI, OHIO, ASSIGNOR TO HOMAN & CO., OF SAME PLACE.

DESIGN FOR A CAKE-BASKET.

SPECIFICATION forming part of Design No. 22,352, dated April 18, 1893.

Application filed February 28, 1893. Serial No. 464,117. Term of patent 3½ years.

To all whom it may concern:

Be it known that I, SETH H. LEAVENWORTH, a citizen of the United States, residing at Cincinnati, in the county of Hamilton and State 5 of Ohio, have invented and produced a new and original Design for a Cake-Basket; and I do hereby declare the following to be a full, clear, and exact description of the same, reference being had to the accompanying drawings, forming a part thereof.

In the drawings, Figure 1 is a sectionized elevation of a cake-basket embodying my design. Fig. 2 is a plan of one fourth of the basket, the remainder of the same being indicated by dotted lines, and the handle being omitted. Fig. 3 is an enlarged section taken through the side of the basket at the line Z—Z, of the preceding illustration.

The body or basket A has at center a pit B, from which a series of main scrolls C, proceed out to the rim of said basket, smaller scrolls D, being located where said scrolls join the edge of said pit. These main scrolls may

be repeated as often as desired, as suggested by the dotted lines C', in Fig. 2.

E, are other, but smaller scrolls, disposed around the margin of the basket, flower ornaments F, being situated between said scrolls E, and the main scrolls C. Furthermore, those portions of the basket included between the 30 pit and rim and the main scrolls C, are slightly waved or corrugated, as shown at G, in Fig. 3.

H is an ornamented base for the basket, and I are feet upon which the base stands.

The handle of the basket is ornamented 35 with scrolls L, L', and flowers M, M'.

I claim as my invention—

The design for a cake-basket, as herein shown and described.

In testimony whereof I affix my signature in 40 presence of two witnesses.

SETH H. LEAVENWORTH.
